(57) **CLAIM**

The ornamental design for: boat table, as shown and described.

DESCRIPTION

FIG. 1 is a top elevational view showing my new design for a boat table, however, it is to be noted that the grain, surface texture and burling form no part of the design;

FIG. 2 is a rear right top perspective view thereof;

FIG. 3 is a front left top perspective view thereof;

FIG. 4 is a left side elevational view thereof;

FIG. 5 is a right side elevational view thereof;

FIG. 6 is a rear elevational view thereof;

FIG. 7 is a front elevational view thereof;

FIG. 8 is a bottom elevational view thereof;

FIG. 9 is a downside up bottom right side perspective view thereof; and,

FIG. 10 is a downside up front perspective view.
